CLAIM

We claim the ornamental design for a router with plunge base, as shown.

DESCRIPTION

FIG. 1 is a front perspective view showing our new design;

FIG. 2 is a top plan view thereof;

FIG. 3 is a front elevation view thereof;

FIG. 4 is a left side elevation view thereof;

FIG. 5 is a rear elevation view thereof;

FIG. 6 is a right side elevation view thereof; and,

FIG. 7 is a bottom plan view thereof.

The broken line showing of a portion of the router is included for the purpose of illustrating environment and forms no part of the claimed design.
